& Film Corporation, New York, N. Y., a corporation of Delaware

No Drawing. Application January 6, 1938, Serial
No. 183,588. In Germany January 21, 1937

3 Claims. (Cl. 95—2)

Our present invention relates to color photography and more particularly to a process of color forming development.

In the production of multi-color pictures the exposed layers have heretofore been developed directly or by reversal development to produce a positive or negative silver image which, after fixing, has been converted into a silver salt and the colored image has then been formed by a color forming developer. In this method layers which do not contain dyestuff components may be used and the latter have been introduced into the developer for producing the colored image. For developing the various color images in their several layers a large number of treating and developing operations is necessary, so that the method is very tedious.

It is therefore one of the objects of this invention to provide a comparatively simple color developing process which, however, enables the operator to make necessary corrections in the color shades and to eliminate undesirable color strains.

Further objects of this invention will become apparent from the detailed description following hereinafter.

The invention is concerned with a process in which there is used a multi-layer photographic material containing in the several layers the suitable dyestuff components for the component pictures and the correct coloring is controlled first by simple or reversal development in the several layers to produce component silver images and then, after fixing and converting the silver into a silver salt, further developing with the color forming developers. As compared with the direct development of the color image in which the number of necessary process steps is smaller this new method has the great advantage of permitting control of the color tints in full daylight. Thus faulty reproduction may without difficulty be avoided and matters of personal preference in the color reproduction may be taken into consideration. For example, in printing a complementary color negative onto a multi-layer positive material containing components an undesirable color strain in the positive may be completely removed by treating the bleached-out positive in succession with different color forming developers. Developers may be selected which differ in their action on the various dyestuff components in the emulsion layers, reacting more quickly with one than with the other. In this case the duration of the development may be adjusted at will and one or the other of the component images may be more or less accentuated. Further, the original black-and-white silver image may be treated with a known reducer or intensifier and thus the density of all or some of the component layers may be varied,

which causes a corresponding change in color tints during the subsequent color forming development.

The developing solutions to be used may either contain different substances suitable for color forming development or the speed of action of one and the same or even different developers may be varied by additions.

Moreover, it is possible to correct the color tint of the image by treatment with a color developer which at the same time contains a dyestuff component which produces a color which is partly lacking or insufficient in the finished color picture. Since in this case the action of the color forming developer is not limited to any particular layer, the method lends itself only to a comparatively small compensation of the color tint.

As dyestuff formers for the silver halide emulsion layers there may be used with advantage dyestuff components which are fast to diffusion with respect to the binding agent of the emulsion owing to the presence of certain radicals in their molecule. As described in U. S. Patent 2,179,238, groups may be introduced into the color components which impart to the molecule of the color former a substantive character. As described in U. S. Patent 2,178,612 the dyestuff components may be made fast to diffusion by introducing into their molecule radicals of highly polymeric carboxylic acids or their derivatives. Moreover, dyestuff components become fast to diffusion when as described in U. S. Patent 2,186,849, there is introduced thereto an aliphatic carbon chain of more than 5 carbon atoms, or, as described in U. S. Patent 2,179,244 polypeptide radicals, or, as described in U. S. Patent 2,186,732 a carbohydrate radical, or, as described in U. S. Patent 2,186,733 the radical of a natural resin, or, as described in U. S. Patent 2,186,851 a sterol radical. Furthermore, dyestuff components fast to diffusion are also obtained when, as described in U. S. Patent 2,186,734 the molecules of the dyestuff components are linked together to yield a chain-like molecule. It is also possible to produce dyestuff components fast to diffusion in manner described in U. S. Patent 2,179,228, in which the dyestuff picture is produced by azo-coupling. Generally such dyestuff components are fast to diffusion which are substituted by radicals of comparatively high molecular weight (2,179,239).

As developing agents there may be used for example the substances described in U. S. Patents Nos. 1,102,028; 2,146,040; 2,163,781; 2,124,612; 2,108,243; 2,122,599; 2,163,820 and 2,163,166.

The following examples illustrate the invention:

Example 1.—A multi-layer film, in which the first silver halide emulsion is pan-chromatically

sensitized and comprises a color component which yields on color forming development a blue image, and the second layer is sensitized for green and comprises a dyestuff component which yields a red image on color forming development and the third layer is not sensitized and comprises a dyestuff component which on color forming development yields a yellow image, is exposed and thereafter developed in normal manner in black-and-white and fixed. After washing and fixing, the film is transferred to a bleaching bath consisting of a solution of cupric chloride of 3 per cent strength; it is then again washed and developed by means of a developer containing 2.5 grams of amino-dimethylaniline and 30 grams of calcined sodium carbonate per liter of water. There is thus produced in each layer the dyestuff image belonging thereto and after again washing the developed silver is bleached by a Farmer's Reducer whereby the pure three-color image remains. As compared with a development in which the first developer yields the dyestuff, the present method has the advantage that any desired usual black-and-white developer may be used as the first developer and in this manner an essentially higher sensitivity attained, since it is known that a color forming developer is less powerful in its developing effect than are the usual black-and-white developers.

Example 2.—If a film treated, for example, in a manner analogous to that described in Example 1 shows an undesirable color strain produced may be by insufficiency of one of the component colors, then the defect in the film may be eliminated by a subsequent treatment. The silver produced simultaneously with the dyestuff formation is bleached out, and a color developer which contains a dyestuff component for the particular color shade lacking in the picture, is employed. For example, if the film, owing to the lack of red, appears too greenish, a developer will be used which in addition to the color forming agent, contains a red dyestuff component, for instance 10 grams per liter of 1-phenyl-3-methyl-5-pyrazolone. If, owing to the lack of blue, the film has a yellow to reddish appearance, then there is added to the developer instead of a pyrazolone the corresponding quantity of α -naphthol.

Example 3.—In cases where it can be foreseen that the finished color film will show an undesirable color shade owing to the predominance of a certain colored light during exposure, this undesirable shade may be eliminated or profoundly modified by adding to the developer, in the same manner as in Example 2, a dyestuff component which yields already during the color forming development that color tint the lack of which in the colored picture would give the undesired color strain. If, for example, it is known that the finished film will show a violet strain, then this strain may be removed or profoundly modified by adding to the color developer 10 grams of aceto-acetic acid anilide per liter.

Example 4.—If it is known beforehand that the finished colored film for one reason or another will show a certain color strain, then it is possible to counteract this color strain by using as a developer a substance which in itself shifts the tint of the picture in a sense complementary to the undesired color strain which is expected. If, for example, it is known that the film for some

reason will have a reddish strain, then there may be used as a developer a solution of 3 grams per liter of 6-methyl-amino-3-toluidine made alkaline with sodium carbonate. By this developer the tint of the color film produced will be shifted towards the green in comparison with a film developed with para-amino-dimethylaniline.

We claim:

1. A process of producing photographic color pictures on multi-layer photographic material comprising a plurality of superposed silver halide emulsion layers containing dyestuff components fast to diffusion, said dyestuff components being capable of forming a dye in the places of the silver picture upon being contacted with a color forming developer, which process comprises exposing said material to light, developing the latent image thus formed with a black-and-white developer, fixing the developed picture, re-converting the formed silver into a silver salt capable of being developed by a color-forming developer which would normally yield dyestuff images having undesired color strains, redeveloping said silver salt by means of a color forming developer while compensating for such undesired color strains by using a developer having the property of shifting the color values to correct said color strains.
2. A process of producing photographic color pictures on multi-layer photographic material comprising a plurality of superposed silver halide emulsion layers containing dyestuff components fast to diffusion, said dyestuff components being capable of forming a dye in the places of the silver picture upon being contacted with a color forming developer, which process comprises exposing said material to light, developing the latent image thus formed with a black-and-white developer, fixing the developed picture, re-converting the formed silver into a silver salt capable of being developed, redeveloping said silver salt by means of a color forming developer containing a dyestuff component, capable of forming a dye with the oxidation product of the developer complementary to the color previously determined to unduly predominate in the final picture, in an amount sufficient to effect the desired depression of the unduly predominant color.
3. A process of producing photographic color pictures on a photographic material comprising three superposed silver halide emulsion layers containing dyestuff components fast to diffusion, said dyestuff components being capable of forming a dye in the places of the silver picture upon being contacted with a color-forming developer, which process comprises exposing said material to light, developing the latent image thus formed with a black and white developer, fixing the developed picture, re-converting the formed silver into a silver salt capable of being developed, redeveloping said silver salt by means of a color-forming developer, bleaching the silver formed by development, determining any undue predominance of one of the three subtractive colors in the three color picture thus produced, and developing again with a color-forming developer containing a dyestuff component capable of forming a dye with the oxidation product of said color-forming developer complementary to the color unduly predominant in said picture.
